UNITED STATES PATENT OFFICE

ALEX P. CARLSON, OF PORTLAND, OREGON

SOUND POST

Application filed August 20, 1925. Serial No. 51,441.

This invention relates generally to musical instruments and particularly to violins and sound posts therefor.

The first object of this invention is to provide an exceedingly simple and efficient means for supporting a violin bridge and propagating the vibrations to the back thereof.

The second object is to make it possible to transmit the maximum amount of vibrations to the back of the violin.

The third object is to construct a special form of base for the sound post which distributes the vibrations over a relatively large area on the back of the instrument.

The fourth object is to employ the resonant qualities of an air-filled base for the purpose of transmitting the vibrations.

The fifth object is to facilitate the adjustment of the sound post by providing a flat area inside of the back of the instrument on which the post can set without detracting from the tone of the instrument.

These, and other objects, will become more apparent from the specification following as illustrated in the accompanying drawing, in which:

Figure 1 is a plan of the body of a violin with the finger-board end broken away. Figure 2 is a longitudinal section taken along the line 2-2 in Figure 1. Figure 3 is a transverse section taken along the line 3-3 in Figure 1.

Similar numbers of reference refer to the same parts throughout the several views.

For the purpose of explaining the invention, there are illustrated the usual violin parts which include the back 10, the sides 11 and the top 12 in which are formed the sound holes 13. The button 14, tail piece 15, finger board 16, strings 17 and bridge 18 are also indicated. On the under-side of the top 12 and under the base strings is the usual base bar 19.

Referring now to my invention, it will be seen to consist of a somewhat tapering hollow base 20 whose bottom edge is shaped to conform with the shape of the back 10 of the violin at the point where the sound post is ordinarily placed. On the flat top 21 of

the base 20 is mounted the short sound post 22 which is approximately under the "E" string just behind the bridge 18 but actually at the point where the desired tone is obtained without regard to its exact position. The post 22 is not secured in any way except by friction.

Those familiar with the setting of sound posts know that this operation is not a very simple matter if an attempt is made to secure the maximum amount and quality of tones without the undesirable sounds. Much of this difficulty is due to the shape of the violin back which requires that the foot of the sound post be shaped accordingly. Should the slopes fail to coincide it is evident that a point contact will be the result instead one having a large area.

I am aware that sound posts have long been employed in the construction and use of violins. I therefore do not claim such devices broadly but I do intend to cover all such forms and modifications thereof as fall fairly within the appended claim.

I claim:

A sound post for violins consisting of a somewhat tapering hollow base having its back-engaging end shaped to fit and adapted to be glued to a violin back; having an air confining cover over said base; and a short solid post on said cover adapted to engage the under side of a violin top.

ALEX P. CARLSON.
